UNITED STATES PATENT OFFICE.

JAY C. RUSSELL, OF FINDLAY, OHIO.

PRIMING DEVICE FOR INTERNAL-COMBUSTION ENGINES.

Application filed January 30, 1923. Serial No. 615,880.

This invention relates to improvements in priming devices for carburetors, and more particularly to means attachable to the overflow pipe of any type of carburetor, for governing and regulating the inflow of the additional air supply through said pipe.

An object of the invention is to provide a suitable valve means in the overflow passage of a carburetor, which may be remotely controlled to enrich the mixture in the carburetor when the valve is closed, and to lean the mixture when the valve is open.

A further object of the invention is to control the flow of air into the carburetor through the overflow pipe and thereby to control the richness of the explosive mixture there formed.

Other objects will appear as the description proceeds.

20 In the accompanying drawings which form a part of my application,

Figure 1 is a side elevation of an automobile engine and carburetor with my invention attached thereto, and

25 Figure 2 is a sectional view of a portion of a carburetor, such as appears in the patent to Holley No. 1,121,630 of December 22, 1914, showing the positioning of the overflow opening and pet cock attached thereto.

30 Like characters of reference are used throughout the following specification and the accompanying claims to designate corresponding parts.

An automobile 1 is provided with a usual 35 type of internal combustion engine 2, and dash board 3.

The carburetor 4 is attached to the intake manifold 5 of the engine 2, and is provided with the overflow pipe or passage 6, which 40 extends between the mixing chamber of the carburetor and the outside thereof.

45 My invention consists of a valve or pet cock 7, removably positioned in the overflow passage 6, and having an operating rod 8 attached thereto, which in turn extends up through the dash board 3, and terminates in an operating handle 9.

50 My improvement is adapted to be used in connection with any type of carburetor, but is shown in Figure 2 of the drawings, as used in connection with a slightly modified form of Holley carburetor, as described and

claimed in Patent Number 1,121,630 of December 22, 1914.

Heretofore the overflow passage in a carburetor was only used to discharge the surplus of fuel if the carburetor became flooded, no thought being given to the admission or controlling of the additional air which enters through the overflow passage and mixes with the main air supply in the mixing chamber. It is my discovery that by placing a valve in the overflow passage, the additional air supply which enters therethrough, may be controlled and regulated to enrich the mixture in the carburetor when the valve is closed, and to lean the mixture when the valve is open. This additional air supply when properly controlled by a valve, materially aids in starting an internal combustion engine, especially in cold weather. When it is desired to start an engine, the valve in the overflow passage is closed to cut off the additional air supply, thereby making a very rich mixture in the carburetor, which facilitates easy starting. When the engine has run a sufficient time to become warmed up to an efficient operating temperature, the valve in the overflow passage will be opened, and kept open during the running period.

Many minor changes in detail of construction may be resorted to without departure from the spirit of the invention.

Having thus described my invention what I claim as new and desire to secure by Letters Patent of the United States is:

1. In combination with an internal combustion engine, a carburetor having a carbureting tube, an air passage formed about said tube, an overflow opening extending from said air passage to the exterior of said carburetor, and means for selectively opening and closing said overflow opening.

2. In combination with an internal combustion engine, a carburetor having a carbureting tube, an air passage formed about said tube, an overflow opening extending from said air passage to the exterior of said carburetor, and a remotely controlled valve for selectively opening and closing said overflow opening.

In testimony whereof I affix my signature.

JAY C. RUSSELL.
